UNITED STATES PATENT OFFICE.

ELMORE D. TICHENOR, OF DETROIT, MICHIGAN.

TOOTHBUSH SHIELD AND DENTIFRICE HOLDER.

Application filed August 18, 1922. Serial No. 582,575.

To all whom it may concern:

Be it known that I, ELMORE D. TICHENOR, a citizen of the United States of America, residing at Detroit, in the county of Wayne, and State of Michigan, have invented certain new and useful Improvements in Toothbrush Shields and Dentifrice Holders, of which the following is a specification, reference being had therein to the accompanying drawings.

This invention relates to a tooth brush shield and dentifrice holder, and my invention aims to provide, as a new article of manufacture, a shield that may be easily and quickly mounted over the bristle end of a toothbrush to protect the bristles and retain the same in a sanitary condition.

My invention further aims to furnish a tooth brush shield with a container for paste, powder or any suitable dentifrice that may be applied to the bristles of the brush by simply rubbing or placing the bristles on the dentifrice, which is also retained in a sanitary condition by being enclosed when not in use.

My invention further aims to provide a simple, durable and inexpensive tooth brush shield which may be placed in position by endwise movement of either the brush or shield, said shield being equipped with an end lid which is sprung to a closed position to prevent accidental displacement of the shield relative to the brush.

The construction entering into my invention will be hereinafter described and then claimed, and reference will now be had to the drawing, wherein—

Figure 1 is a perspective view of the tooth brush shield showing its lids open, and the preferred manner of providing the brush bristles with dentifrice;

Fig. 2 is a longitudinal sectional view of the shield as mounted on a tooth brush;

Fig. 3 is a cross sectional view of the same, and

Fig. 4 is a perspective view, of the shield as mounted on a tooth brush.

A combined shield and holder in accordance with my invention may be made of celluloid, imitation ivory, aluminum or any light and durable material that can be retained in a sanitary condition and possess sufficient rigidity to prevent the shield from being crushed when carried in the pocket,

packed in a traveling bag, or handled in the usual manner.

I provide a casing having a bottom wall 1, side walls 2 and 3, and end walls 4 and 5, the end wall 4 being the full depth of the casing and the end wall 5 serving the upper portion of the casing so as to provide two openings 6 and 7, the former providing clearance for the back 8 of a tooth brush and the latter opening being normally closed by a hinged lid 9 after the bristles 10 of the brush are within the casing.

The side walls 2 and 3 are provided with opposed longitudinally disposed indent portions forming ledges 11 on which may slide or rest the side edges of the tooth brush back 8 and, if necessary, prevent the tips of the bristles 10 from contacting with the bottom wall 1 of the shield. The side walls 2 and 3, at the open end of the casing, are undercut to form lid shoulders 12, and the lid 9, which is preferably hinged or otherwise pivotally connected to the bottom wall 1, is adapted to be sprung under the shoulders 12, as best shown in Fig. 4. To facilitate opening the lid 9 it has small side lugs or ears 13 projecting outwardly under the ledges 11 of the casing.

Set between the walls 2 and 3 is a dentifrice container or holder having a bottom wall 14 and side walls 15 and 16 said walls 15 and 16 cooperating with the walls 4 and 5 in forming a chamber in which paste, powder or any other dentifrice may be placed. In practice, I may make the side wall 3 of a piece of material that can be bent upon itself to form the walls 16, 14 and 15 and in so forming the walls 3 and 16 provide a barrel 17 cut away to provide clearance for barrels 18 of a top lid 19. The barrels 17 and 18 may align and be hingedly held relative to each other by a pintle 20.

The free edge of the top lid 19 is formed with a clip or clasp 21 adapted to snap over an upstruck keeper 22 of the wall 2 or any other suitable means may be employed for retaining the top lid 19 closed. With the lid open the bristles 10 of the brush may be placed on the dentifrice, as indicated by dotted lines in Fig. 1, and after the brush has been used the shield or the brush may be shifted endwise to inclose the bristles within the shield. The top lid 19 having been previously closed the end lid 9 can

now be swung to a closed position, as shown in Figs. 2 and 4 and the shield cannot become accidentally displaced relative to the brush.

5 By making the shield larger and slightly changing its configuration it may be mounted on a hair brush and the container used for holding a small comb, hairpins or other articles, and for this reason, I do not care 10 to confine my invention to the precise construction shown, other than defined in the appended claims.

What I claim is:—

1. A brush shield comprising a casing 15 adapted to be placed endwise on a brush, said casing having a chamber throughout its length disposed parallel to a brush in said casing, said casing having its side walls

provided with end shoulders, an end lid hingedly connected to the bottom wall of 20 said casing at the inner end of said casing and adapted to swing upwardly under the end shoulders of said casing to retain the brush in the shield, and a top lid for the chamber of said casing.

2. A brush shield as called for in claim 1, wherein said casing has its side walls inbent 25 to form a bristle receiving compartment of less width than said chamber.

In testimony whereof I affix my signature 30 in presence of two witnesses.
